UNITED STATES PATENT OFFICE.

JOHN C. DAYNIX, OF PHILADELPHIA, PENNSYLVANIA.

AEROPLANE.

Application filed December 20, 1923. Serial No. 681,769.

To all whom it may concern:

Be it known that I, JOHN C. DAYNIX, a citizen of the United States of America, residing at Philadelphia, in the county of Philadelphia and State of Pennsylvania, have invented certain new and useful Improvements in Aeroplanes, of which the following is a specification.

This invention relates to flying machines of the heavier than air type, and it has more particular reference to machines of the multiplane variety; the primary object being to provide an aeroplane having a greatly increased maintenance surface with a relatively decreased wing spread.

Another object of this invention is to provide a multiplane having relatively long superposed planes, the longitudinal sides whereof are transversely curved whereby equilibrium in flight is better maintained.

A further object of this invention is to provide a multiplane equipped with buoyancy instrumentalities, whereby the factor of safety is considerably increased.

A still further object of this invention is to provide a multiplane having an automatic stabilizer whereby said plane when in flight is effectively maintained on an even keel.

Further objects are to increase the carrying capacity; to provide an aeroplane having a plurality of propellers so arranged as to bank the air substantially in alignment with the longitudinal axis of the machine, whereby possible adverse effects, when encountering cross-currents, are reduced to a minimum; to provide a plane of the type referred to with means whereby an aquatic landing can be effected with perfect ease, in addition to rendering the machine normally unsinkable; and to provide a multiplane having a novel means whereby a column of more or less compressed air is longitudinally directed to effect automatic control of the stabilizing equipment.

Numerous other objects, and attendant advantages, will be hereafter referred to, or become obvious from the following detailed description of one practical embodiment of my invention, while the scope thereof will be equally apparent from the subjoined claims.

In the further disclosure of my invention reference is to be had to the accompanying sheets of explanatory drawings, constituting a part of this specification; and, in

which like characters of reference designate the same or corresponding parts in all the views.

Figure 1—is a more or less diagrammatic sectional plan of a multiplane embodying the essential features of my invention, certain parts being removed to better disclose the underlying elements. 60

Figure 2—is a transverse section taken approximately on the line 2—2 in Figure 1, as viewed in the direction of the arrows; and,

Figure 3—is a longitudinal central section thereof. 70

Referring more in detail to the drawings it will be seen that my novel aeroplane comprises a body or fuselage 1, of tubular cross section divided at intervals by partitions 2, to provide fore and aft compartments, comprehensively designated by the numerals 3, 4 respectively, and an intermediate or amidship division 5, for accommodation of the stabilizer instrumentality hereinafter fully described. On an examination of Figure 2 more particularly it will be seen that the body or fuselage 1 surmounts a longitudinal tank 6 that is conveniently sub-divided into sections for the storage of liquid fuel, oil and other accessories; as well as providing adequate capacity for mail, baggage or other materials to be transported. Furthermore, the tank 6 is preferably shaped in its base with an inward transverse curvature 7 that snugly 80 seats on a complementary convexity 8 running centrally the entire length of a lower deck or platform 9. This platform 9 is provided fore and aft of its underside with parallel spaced and air-tight pontoons 10, 10 which may be filled with compressed air to add to the buoyancy of the machine. Appropriate recessions 11, 11 are provided in the pontoons 10, 10 to house and journal the landing wheels 12, 12. In connection with the pontoons 10, 10, I may associate compressed air engines adapted to operate the landing wheels 12, 12 and thereby assist initial ascent for flight, but such engines are not shown, as their application will be 105 readily understood by those acquainted with aviation.

Surmounting the aforesaid lower deck or platform 9, and abutting the side walls of the tank 6, and lower part of the fuselage 1, are open ended tubes 13, 13 conveniently—though not essentially—rectangular in

cross-section, that serve a purpose later on explained. The upper wall of these longitudinally spaced tubes 13, 13 is co-extensive with the lower plane or spaced aerofoils 14 5 that are made of suitable material having the necessary degree of strength and lightness. In connection with this lower plane or spaced aerofoils 14, 14, as will be best seen from Figure 1, I preferably make the 10 same of oblong configuration in plan and extending the major portion of the length of the body or fuselage 1. Likewise, it is noteworthy that the major dimension of the plane or spaced aerofoils 14, extends longitudinally of the machine, in contradistinction with the prevailing practice of making the wing spread the greater dimension. Furthermore, I desire to particularly emphasize the peculiar cross-section of the 15 lower plane or spaced aerofoils 14,—as will be best appreciated from Figure 2—the same being downwardly cambered or curved along their outer longitudinal portions from their alignment with the outer vertical walls of the tubes 13, 13 and to which they are securely braced by brackets or struts 15. This downward curvature of the aerofoils 14 is varied according to the capacity of the machine and has a dual function; namely, to bank the air during flight 20 below the machine to enhance its buoyancy; as well as to direct slightly compressed air currents transversely inward from the sides of the machine for a purpose later on referred to.

Mounted in spaced relation, by means of vertical stanchions 16—and cross braces 16'—are parallel superposed planes or aerofoils 17, 18 of equal and corresponding configuration to the composite lower plane; or, in other words, said superposed aerofoils 17, 18 in superficial outline are complementary to that of the lower plane. However, it is to be noted these aerofoils 17, 18 45 only have their edges overhanging the outermost stanchions 16 downwardly curved, with a greater radius than that of the lower plane. Or, the downward curvature may be graduated from the lower plane upwards: For example, the curvature arc for the longitudinal edges of the intermediate plane or aerofoil 17 may be greater than that of the lower aerofoils 14, with the curvature for the uppermost plane or aerofoil 18 of a still 50 greater radius. Thus, it will be readily understood that the air, when the machine is in flight, will according to its density or rarity be more or less medially banked and compressed relative to the longitudinal axis 55 of the machine. This feature I deem of great importance as it materially enhances the general buoyancy of my machine during flight, while countering adverse cross currents that have a tendency to effect its deviation from an even keel.

The motors 19, 20, 21 of which, according to the embodiment of my invention illustrated, I employ six, are arranged in pairs—as shown. That is to say, a pair of motors 19 are located well forward of the machine 70 and suitably mounted in the well known manner upon the lower plane or spaced aerofoils 14, with a complementary pair 21 similarly located well to the rear; whereas the intermediate pair of motors 20 are similarly disposed substantially amidships on the intermediate plane or aerofoil 17. This disposition of the motors in spaced arrangement and stepped alignment also has its peculiar significance, namely, the relative 75 distribution of the load and dead weight; as well as an increased flying capacity for the machine. Furthermore, in the event of a breakdown or other adverse happening to any one or more of the motors 19, 20, 21 80 during flight, the same can be promptly shut down and repaired, or a safe descent effected 85 with the aid of the remaining motors.

Fore and aft of the aforesaid body or fuselage 1 and at each side thereof I fit 90 stabilizer wings 22, 22 and 23, 23 respectively, the same occupying a co-extensive plane—as will be readily appreciated from an examination of Figure 3, more particularly. Transversely of the body or fuselage 95 1, and in the same plane as the stabilizer wings 22, 23, I journal, in close relation thereto, front and rear shafts 24, 25 respectively, the former of which is connected by bell cranks 26 with the elevating rudders 100 or wings 27, 27 suitably hinged at 28 to the rear transverse edges of the aforesaid stabilizer wings 22, 22, as will be readily understood by those conversant with the art. The shaft 24 is also operatively connected 105 by a linkage 29 to the automatic stabilizing instrumentality comprehensively designated by the numeral 30, and hereafter described in detail. Similarly the rear shaft 25 is adapted to actuate elevating rudders or 110 wings 31, 31, with the exception that said shaft constitutes the pivotal member proper therefor. This rear shaft 25 is conveniently fitted, or has secured substantially central 115 thereof a double arm fork ended member 32 which is connected by crossed links or ties 33, 34 with a companion member 35 fixed to a rock shaft 36 journaled in bearings 37, rigidly mounted in the upper part or to the roof 38 of the hereinbefore referred to 120 midship division or compartment 5. As best seen from Figure 3, the aforesaid double armed members 32, 35 constitute diametric attachments on the respective shafts 25, 36; while it will be noted that the forward end of the tie 33 is pivotally connected 125 to the upwardly directed fork arm of the member 35 and downwardly disposed fork arm of the member 32. On the other hand the front end of the tie 34 connects the lower 130

fork arm of the member 35 with the upwardly directed fork arm of the member 32. The crossing of the ties 33, 34 is thereby effected in parallel planes for a purpose 5 hereafter fully explained, while it will be obvious they may be fitted with turnbuckles or other appropriate means, whereby they can be accurately tensioned and adjusted.

The steering rudder 39 is pivotally supported by a rudder post 40, at the rear end of the machine, in the well known way, and in central vertical alignment with said post intermediate the upper supporting planes or aerofoils 17, 18, I arrange what may be 10 conveniently termed a fixed rudder 41. This fixed rudder 41 cooperates with the steering rudder 39, and certain instrumentalities hereafter fully described, in greatly facilitating accurate steerage of the machine 15 under all service conditions. Connected to opposed lateral lugs 42 on the steering rudder 39 are chains or cables 43—one at each side thereof—that are guided about idler anti-friction sprockets or sheaves 44, 45, 46 20 mounted at suitable intervals within the body or fuselage 1. After passing the idler sprockets or sheaves 46 the aforesaid chains or cables 43 inwardly converge and pass in opposed relation around a compound sheave 47 securely keyed or otherwise fixed on a 25 vertical shaft 48; and thence said chains or cables are forwardly conducted to a similar sprocket or sheave 49 mounted on the steering column 50 conveniently located in the 30 cockpit adjacent the pilot's seat 51. Thus it will be readily understood that by turning the hand wheel 52 on the steering column 50, the rudder 39 can be manipulated and swung to the right or left hand with 35 ease whereby steering is easily effected. Or the column 50 may be power actuated in any of the well known ways, as will be quite obvious.

Referring back to the vertical shaft 48 it is to be noted that the same is journaled at the lower end in an appropriate anti-friction footstep or bearing 53—Figure 3—and that near the upper end thereof—where it is similarly journaled at 55—I key or otherwise secure a pinion 54 that meshes with a toothed sector 56 fixed on the pendent end of a stub shaft 57 having appropriate bearing in the roof of the body or fuselage 1. Thus it will be obvious to anyone in the least conversant with mechanical gears that rotation of the shafts 48 and 56 will be in reversed direction, or with a clockwise and counterclockwise path of movement, and vice versa.

60 Longitudinally and rigidly supported by bearing brackets 58 on the intermediate supporting plane or aerofoil 17 is what I term an air current compressing device 59 the function and structure whereof will now be 65 explained. This air current compressing

device 59, as will be best seen from Figures 1 and 3, consists of a tubular casing or shell embracing front and rear inwardly converged portions 60, 61 merging to an intermediate spherical portion 62. Vertically co-axial through this portion 62 the aforesaid stub shaft 57 extends and is journaled in appropriate bearings mounted on the supporting planes or aerofoils 17, 18 in any suitable manner to ensure rigidity. Rearwardly 70 directed in the converged portion 61 is an auxiliary steering rudder 63 that is suitably secured to the stub shaft 57, and aligning therewith above said portion is a second or supplemental rudder 64. These auxiliary and supplemental Rudders 63, 64 are preferably—though not essentially—braced by straps 65 for synchronous movement, and it is to be particularly noted that they are likewise 75 coordinated by means of the gears 56, 54 and operatively connected instrumentalities for simultaneous reverse directional movement with the main steering rudder 39. The force and effect of this reverse ordinated movement for the rudders 39, 62 and 63 is to enhance and make more positive the steering of my novel aeroplane, as it will be readily understood that when said rudders are all 80 in neutral position, during "direct ahead" flight, the air entering the forward converged portion 60 of the device 59 will be comparatively compressed and directed through the rearward and reversely converged portion 61 towards the propellers of 85 the upper engines 20, 20, as well as directly astern relative to the main steering rudder 39, thus materially aiding in preventing deflection of said rudder by adverse cross currents. Furthermore, it is to be particularly 90 observed that by provision of the forwardly disposed device 59 and associated rudders 63, 64 the forward and right or left hand bow or head movement of the aeroplane is rendered more sensitive and accurate, whereby navigation is accomplished 95 with far greater accuracy and certitude than has hitherto been possible. Still further the directing of a column of semi-compressed air longitudinally co-axial through the upper aerofoils or supporting planes 17, 18 considerably increases the buoyancy, stability, and 100 flight speed, while aiding steering by banking the air against the fixed and steering rudders 41, 39, when the latter is deflected 105 to either hand.

Referring once again to the automatic stabilizing instrumentality 30 hereinbefore referred to, and which fundamentally functions to maintain the machine on an even 110 keel during flight, it will be best seen from Figure 3 that it comprises a "dead" weight or pendent ball 66 adjustably or otherwise supported by a rod or bar 67 freely pivoted at 68 to a yoke 69 whereby said rod or bar is 115 120 125 130

capable of lateral or athwartship swinging movement. The yoke 68 is, in turn, pivotally suspended at 70 to the lower arm or arms of the hereinbefore referred to double 5 armed companion member 35, whereby it is rendered capable of fore and aft swinging movement. Thus it will be readily seen that the ball 66 is suspended by a substantially universal connection thereby affording a 10 novel stabilizing means that will automatically accommodate itself, and positively control the elevating wings or rudders 27, 31. Or, in other words, no matter what flight conditions may be encountered the device 30 15 will always automatically function to keep the wings or rudders 27, 31 in horizontal position and thereby effectively preventing nose or tail dives. In this connection and to provide for elevation and descent, I pivotally connect a linkage or rod 71 from a lug 20 72 on the aforesaid yoke 69 to a short lever 73, in turn fixed to the forward transverse shaft 24, said linkage or rod having an associated control lever 74 pivoted at 75 in juxtaposition to the pilot's seat 51. Thus it will be readily seen that the pilot can easily manipulate the elevating wings or rudders 27, 31 for ascent and descent, but that during flight said rudders will be automatically 25 30 controlled by the stabilizer device 30, whereby the machine will be kept on an even keel.

In connection with the hereinbefore described open-ended tubes 13, 13, I preferably fit a series of spaced shutters 76 having a 35 rearward inclination—as shown in Figure 3—the same being conveniently—though not essentially—hinged at 77 to the top of said tubes and under appropriate control, whereby they may be raised and lowered at 40 will, or locked in an intermediate position as illustrated. The necessary means for controlling these shutters 76 is not shown, as it will be apparent to anyone schooled in the art and constitutes no fundamental feature 45 of the present invention. Obviously, when the shutters 76 are hinged they will be co-ordinated for simultaneous operation, while it will also be apparent that by their provision I have evolved a novel means for 50 choking and partially compressing the volume of air flowing therethrough during flight, whereby the machine is rendered more buoyant. Still further, it will be equally clear that by closing or partially closing 55 down the shutters 76 when effecting a landing that they will function as an effective retarding or braking means, with the resultant better and safer control of the machine.

60 Although I have shown and described a particular construction, combination and arrangement of multiplane, I do not desire to be limited or restricted in any sense to this particular form of machine, but wish it ex-

pressly understood this specification includes 65 within its purview all reasonable variations and modifications that may be fairly construed as falling within the scope of the subjoined claims.

Still further, it will be obvious that an 70 aeroplane embodying the features of construction hereinbefore described includes a greatly increased sustaining plane area which is located relative to the fuselage in such wise as to positively ensure the maximum 75 stability and buoyancy. Furthermore, the banking of the air during flight directly longitudinal of the relatively cambered sustaining planes, in combination with the stepped balancing of the motors—as set 80 forth—ensures a machine that is economical to construct, durable, very efficient in action, and withal, easier to handle and steer than has hitherto been possible.

Having described my invention what I 85 claim as new and desire to secure by Letters Patent is:-

1. A flying machine having superspaced supporting planes with the major dimension lengthwise thereof, a fuselage and co-extensive spaced air tubes having declined shutters, and said tubes surmounting air tight pontoons fitted with landing wheels.

2. A flying machine having superspaced supporting planes with the major dimension lengthwise thereof, a fuselage and co-extensive spaced air tubes with intermediate storage capacity, co-ordinated adjustable shutters in the air tubes, and said tubes surmounting pontoons provided with inset 100 landing wheels.

3. A flying machine having superspaced supporting planes with the major dimension lengthwise thereof, a fuselage and co-extensive spaced air tubes with intermediate 105 storage capacity, co-ordinated adjustable shutters in the air tubes, said tubes surmounting pontoons provided with inset landing wheels, and means whereby said wheels may be power operated to facilitate 110 an ascent.

4. A flying machine having superspaced supporting planes with the major dimension lengthwise thereof, a fuselage and co-extensive air tubes with intermediate storage 115 capacity, declined shutters in the air tubes, lateral stabilizers for the machine having pivotally mounted elevating wings, and a co-ordinated stabilizing device whereby said elevating wings are automatically actuated 120 during flight to maintain the machine in equilibrium.

5. A flying machine having superspaced aerofoils with the major dimension lengthwise thereof, a fuselage and co-extensive air tubes fitted with declinable shutters, lateral stabilizer planes having pivotally mounted elevating wings, and a co-ordinated device 125

- functioning to maintain the machine in equilibrium by automatic actuation of said wings during flight.
6. A flying machine having superspaced 5 aerofoils with the major dimension lengthwise thereof, a fuselage and co-extensive air tubes fitted with declinable shutters, lateral stabilizer planes having pivotally mounted elevating wings, and a co-ordinated device 10 functioning to maintain the machine in equilibrium by automatic actuation of said wings during flight, said device comprising a transverse rock shaft and pendent double arm weighted member, a double armed member 15 on the pivot of the rear elevating wings, crossed ties connecting said double armed members, and a co-operative connection between the weighted member and the pivot of the forward elevating wings.
- 20 7. A flying machine having superspaced aerofoils with the major dimension lengthwise thereof, a fuselage and co-extensive air tubes fitted with declinable shutters, lateral stabilizer planes having pivotally mounted 25 elevating wings, and a co-ordinated device functioning to maintain the machine in equilibrium by automatic actuation of said wings during flight, said device comprising a transverse rock shaft and double armed 30 member, a yoke and heavy body pendent to said member adapted for universal motion, a complementary armed member on the pivot of the rear elevating wings, crossed tie rods between the double armed members, and a 35 cooperative linkage connecting said pendent body with the pivot of the forward elevating wings.
8. A flying machine having superspaced 40 aerofoils with the major dimension lengthwise thereof, a fuselage and co-extensive air tubes fitted with declinable shutters, lateral stabilizer planes having pivotally mounted elevating wings, and a co-ordinated device 45 functioning to maintain the machine in equilibrium by automatic actuation of said wings during flight, said device comprising a transverse rock shaft and double armed member, a yoke and heavy body pendent to 50 said member adapted for universal motion, a complementary armed member on the pivot of the rear elevating wings, crossed tie rods between the double armed members, a co-ordinating linkage connecting said pendent body with the pivot of the forward elevating 55 wings, and means whereby the wings may be manually deflected.
9. A flying machine having superspaced 60 supporting planes with the major dimension lengthwise thereof, a fuselage and co-extensive air tubes fitted with declinable shutters, spaced lateral stabilizers provided with co-operative elevating wings, means for 65 automatically controlling said wings during flight, a main steering rudder, and an air compressing device provided with an auxil-
- iary steering rudder intermediate a pair of the supporting planes.
10. A flying machine having superspaced 70 supporting planes with the major dimension lengthwise thereof, a fuselage and co-extensive air tubes fitted with declinable shutters, spaced lateral stabilizers provided with co-operative elevating wings, means for automatically controlling said wings during 75 flight, a main steering rudder, and an air compressing device provided with an auxiliary rudder intermediate a pair of the superspaced planes, said auxiliary rudder being adapted for simultaneous but reflex movement with respect to the main steering rudder.
11. A flying machine having superspaced 80 supporting planes with the major dimension lengthwise thereof, a fuselage and co-extensive air tubes fitted with declinable shutters, spaced lateral stabilizers provided with co-operative elevating wings, means for automatically controlling said wings during 85 flight, a main steering rudder, an air compressing tube having an auxiliary rudder therein intermediate a pair of the superspaced planes, said auxiliary rudder being simultaneously movable with the main steering rudder but in a reflex direction.
12. A flying machine having superspaced 90 supporting planes with the major dimension lengthwise thereof, a fuselage and co-extensive air tubes fitted with declinable shutters, spaced lateral stabilizers provided with co-operative elevating wings, means for automatically controlling said wings during 95 flight, a main steering rudder, a tube comprising inwardly convergent longitudinal portions intermediate a pair of the superspaced planes, an auxiliary steering rudder in the rear convergent portion, and means adapted to reversely deflect said auxiliary rudder simultaneously relative to the main rudder.
13. A flying machine having superspaced 100 supporting planes with the major dimension lengthwise thereof, a fuselage and co-extensive air tubes fitted with declinable shutters, spaced lateral stabilizers provided with co-operative elevating wings, means for 105 automatically controlling said wings during flight, a main steering rudder, a tube comprising front and rear opposingly converged sections intermediate a pair of the superspaced planes, an auxiliary steering rudder in the rear section, a supplemental aligning rudder exteriorly thereabove, and mechanism reversely co-ordinating movement of 110 said auxiliary and supplemental rudders relative to the main steering rudder.
14. A flying machine having superspaced 115 supporting planes with the major dimension lengthwise thereof, a fuselage and co-extensive air tubes fitted with declinable shutters, spaced lateral stabilizers provided with co-operative elevating wings, means for 120 automatically controlling said wings during flight, a main steering rudder, and an air compressing device provided with an auxil-

- with co-operative elevating wings, means for automatically controlling said wings during flight, a main steering rudder, a tube comprising front and rear opposingly converged 5 sections intermediate a pair of the super-spaced planes, an auxiliary steering rudder in the rear section, a supplemental aligning rudder exteriorly thereabove, the aforesaid tube being located well forward for directing 10 a column of air longitudinally of the machine.
15. A flying machine having superspaced aerofoils with the major dimension lengthwise thereof, and the longitudinal edges downwardly cambered for banking the air during flight, in combination with means for directing a column of semi-compressed air 15 between a pair of the superposed aerofoils,

and shutter controlled air tubes adapted to retard flight momentum when effecting a 20 landing.

16. A flying machine having superspaced aerofoils with the major dimension lengthwise thereof, and the longitudinal edges downwardly cambered for banking the air 25 during flight, in combination with means for directing a column of semi-compressed air between a pair of the superposed aerofoils, and shutter controlled air tubes adapted to retard flight momentum when effecting a 30 landing, and the further combination of means for automatically ensuring equilibrium during flight.

In testimony whereof, I affix my signature this 18th day of December, 1923.

JOHN C. DAYNIX.
